UNITED STATES PATENT OFFICE.

JOHN T. KENNEDY, OF CARL, KANSAS.

DESIGN FOR A NECK-YOKE BRACKET.

SPECIFICATION forming part of Design No. 32,962, dated July 17, 1900.

Application filed June 18, 1900. Serial No. 20,600. Term of patent 14 years.

To all whom it may concern:

Be it known that I, JOHN T. KENNEDY, a citizen of the United States, residing at Carl, in the county of Jackson and State of Kansas, have invented and produced a certain new and original Design for Neck-Yoke Brackets; and I do declare the following to be a full, clear, and exact description of the invention, such as will enable others skilled in the art to which it appertains to make and use the same.

Figure 1 is a perspective view of the bracket. Fig. 2 is a side view thereof.

1 in the drawings represents the neck-yoke bracket, comprising a strap or band which has the general form of a hook, being formed with upper and lower parallel arms 2 and 3 of unequal length and connected at their forward

ends by a curved return portion 4. The upper arm 2 is the longer one and is provided with a deflected portion 5, extending upwardly and forming an inverted-U-shaped saddle or loop. This saddle or loop constitutes an arch closed at its base by a bridge-piece 6.

Having thus described my invention, what I claim is—

The design for a neck-yoke bracket, substantially as herein shown and described.

In testimony whereof I have hereunto set my hand in presence of two subscribing witnesses.

JOHN T. KENNEDY.

Witnesses:

FRANK BOTHE,
ROBERT KENNEDY.
